UNITED STATES PATENT OFFICE.

JOSEPH E. SNELL, OF NEWARK, NEW JERSEY, ASSIGNOR TO HENRY STEERS, INC.,
OF NEW YORK, N. Y., A CORPORATION OF NEW YORK.

PIER CONSTRUCTION.

1,391,516.

Specification of Letters Patent. Patented Sept. 20, 1921.

Application filed April 19, 1920. Serial No. 374,990.

To all whom it may concern:

Be it known that I, JOSEPH E. SNELL, a citizen of the United States, residing in Newark, county of Essex, and State of New Jersey, have invented a certain new and useful Pier Construction, of which the following is a specification.

This invention relates to improvements in wharves, piers, quays, bulkheads, bridges and analogous waterfront structures and has for its objects—

First, to provide a cheap construction which may be built with pre-cast reinforced concrete elements whereby underwater construction will be avoided.

Second, to prevent injury to the structure from fire due to the burning of inflammable substances floating on the surface of the water.

Third, to cheapen the construction of such a structure and

Fourth, to protect the fire resisting device from injury by drift wood or vessels.

These and further objects will more fully appear from the following specification and accompanying drawings considered together or separately.

This application is a continuation in part of an application filed by me on or about the 4th day of December, 1916, and given Serial Number 134,837.

In the drawings—

Figure 1 is a side elevation of a portion of a pier embodying my invention.

Fig. 2 is a sectional view on the line 2, 2 of Fig. 1.

Fig. 3 is a plan view of the portion of a curtain.

Fig. 4 is a perspective view of one of the sections of a curtain.

Fig. 5, shows a modification.

In all of the views like parts are designated by the same reference character.

In carrying out my invention I provide a pier 1 with a fireproof curtain 2. The curtain is arranged preferably vertically along the front and sides of the pier. It extends from below the level of mean low water up to the concrete retaining wall of the pier when such is employed. The pier in the embodiment chosen for illustration is formed with wooden piles, caps and deck. This latter is placed as near to the mean low water line as possible. It will be wet at each tide, but I have found in practice that if gaso-

line or similar fuels are floating upon the water in quantities, and are ignited, that a pier so made will catch afire and burn even if the caps and deck are wet. By arranging the fireproof curtain to extend from below the mean low water line 3 up to the concrete retaining wall 11, and making it extend down sufficiently far so that it will always be under the surface of the water, the oils floating on the surface thereof cannot get under the dock and burn it. The details of construction are shown in the embodiment of the invention illustrated. The pier is supported upon piles 5. These are sawed off close to the mean low water level 3. The side bearing piles 5^a are sawed off somewhat shorter and support the side cap 6. The cross caps 7 are supported on the side cap and also the upper ends of the piles 5. The deck 8 is then laid on the cross caps. The outer member of the deck is in the form of a chine piece 9 preferably thicker than the deck planks. On the deck is a key 10 and surrounding the key and chine piece is the concrete retaining wall 11. This is suitably molded in place in the usual manner. On the deck and behind the wall is the usual earth fill and ballast as illustrated. and on the latter are illustrated the ties and rails of the railway carried by the pier. On the outer upper edge of the retaining wall is shown a backing log 14 and on its surface are bolted fender wales 15 which support fender chocks 16; between the chocks are arranged fender piles 17. These piles serve as a means for protecting the fireproof curtain from injury due to floating logs, drift wood or vessels.

The improved curtain is preferably made of reinforced concrete. It is made in sections of suitable length so as to be conveniently handled. Adjacent to the upper edge of the curtain is a ledge 18 preferably molded integrally with the rest of the curtain and extending at a right angle thereto. Within the curtain are suitable deformed metal reinforcements 19. These reinforcements may be bent to L shape so that they extend upward through the curtain and also through the ledge. Suitable pipe thimbles 20 are located at proper intervals in the curtain and ledge for admission of fastening bolts. The bolts 22 pass through the pipe thimbles in the side of the curtain and also through the side cap 6 which forms a back-

ing for the curtain between the piles 5^a so that each section of the curtain, however short it may be, is supported by at least one bolt 22. The bolts 23 pass through the ledge 5 of the curtain and through the chine piece 9. The bolts are set up with suitable fastenings, for example, the washers and nuts illustrated.

In the vertical edges of each curtain section 10 is a vertical groove 24. This groove is open at the top but closed at the bottom as illustrated in Fig. 4. The purpose of this groove is to contain grouting introduced from the top after the sections are assembled. This grouting will act as a key to close the joint between contiguous sections and also to add strength to the entire structure.

In assembling the device, after the chine 20 piece and decking are laid, the curtain is lowered in place and rests with its ledge in engagement with the top of the chine piece and its body portion resting against the outer side of the side cap 6. It is then 25 bolted in place. In order that the workmen may reach the horizontal bolts 22 and the lower ends of the bolts 23, one or more of the deck planks adjacent to the chine piece should not be placed in position until the 30 said bolts are in place and the nuts set up. The concrete retaining wall is then molded in position in the usual manner with anchor bolts 25 projecting from its outer face, the concrete engaging with the eyes 20 and the 35 upper ends of the bolts 23 as well as with the edges of the curtain. The backing log 14 and fender wales 15 may then be bolted in place after the concrete is set and the molds are removed. When completed the pier will 40 have the appearance of a concrete wall extending from the shore line outward and down to and below the mean low water line. It is, therefore, impossible for inflammable substances floating on the surface of the 45 water to get under the pier.

It will be understood that the structure shown in Fig. 3 is but a portion of one side of a pier. The complete structure extends outward from the shore and the curtain encircles all of that portion of it with which 50 the water is in contact, in other words, the structure is provided with a fireproof belt which extends to the level of mean low water and prevents burning substances from reaching the under side thereof.

While I have shown a concrete retaining wall carried on the deck I do not desire to limit myself to such construction. The retaining wall may be of any suitable material 60 or may be dispensed with altogether. The deck may be situated above high water mark and form the surface of the pier, in which case the curtain will extend from above high water to below mean low water. The retaining wall may be of wood, if desired, as 65

even if such a wall should take fire the flames may, on account of the accessibility of the wall, be easily extinguished.

In the modification shown in Fig. 5, the wall 11^a instead of being a retaining wall is 70 shown as the wall of a superstructure, and may be extended upward indefinitely. The ties 12^a of the railroad structure may be supported in the wall 11^a and a roof, if desired, 75 may be supported on the same wall at a distance above the tracks. In this embodiment of the invention the deck 8^a will be the floor of the first story of the pier, and may be above the high water level as shown in Fig. 5, or it may even be below the high water 80 level as shown in Fig. 2.

In accordance with the provisions of the patent statutes I have described the principle of my invention, together with the apparatus which I now consider to represent 85 the best embodiment thereof, but I desire to have it understood that the apparatus shown is merely illustrative, and that the invention may be carried out in other ways.

Having now described my invention what 90 I claim as new and desire to secure by Letters Patent, is:

1. A pier comprising a deck of inflammable material, inflammable supports for supporting the deck above water, and a pre- 95 cast reinforced concrete curtain carried by and depending below the deck and below the water line, and means between the levels of high and low water for securing the curtain to the support.

2. A pier comprising a deck of inflammable material, inflammable supports for supporting the deck above water, and a pre- 105 cast reinforced concrete curtain carried by and depending below the deck and below the water line, and means between the levels of high and low water, for securing the curtain to the support, the said curtain being composed of short sections arranged end-to-end and grouted to form a unitary structure. 110

3. A pier comprising a deck of inflammable material supported above water on inflammable piles, a curtain of pre-cast reinforced concrete inclosing all of that portion of the pier above the water, said curtain ex- 115 tends below the level of low water, the curtain being composed of short sections each having an angular extension for engagement with the upper surface of the deck, the sections being arranged end-to-end and extending from the shore line at one side of the pier around the entire structure to the shore line at the opposite side, the vertical joints between the sections being grouted to make said joints waterproof, bolts for securing 125 the extensions to the deck, and bolts for securing the sections to the structure below the deck.

4. A pier comprising a deck of inflammable material supported above water on in- 130

- flammable piles, a curtain of pre-cast reinforced concrete inclosing all of that portion of the pier above the water, said curtain extending below the level of low water, the curtain being composed of short sections each having an angular extension for engagement with the upper surface of the deck, the sections being arranged end-to-end and extending from the shore line at one side of the pier 5 around the entire structure to the shore line at the opposite side, the vertical joints between the section being grouted to make said joints waterproof, nipples embedded in the extensions, bolts extending through the nipples 10 for securing the extensions to the deck, nipples extending through the sections below the deck, and bolts passing through said nipples for securing the sections to the structure below the deck.
- 20 5. A pier comprising a deck of inflammable material, a concrete wall, extending above the high water level and secured to and supported on said deck along the outer edges thereof from the shore line at one side of the pier around the entire structure to the shore line at the opposite side, a plurality of inflammable piles for supporting the deck above the low water level, and a curtain composed of pre-cast reinforced concrete sections 25 extending from the concrete wall down below the low water level and having their upper ends embedded in the wall to thereby anchor the curtain in place.
- 30 6. A pier comprising a deck of inflammable material, a concrete wall, extending 35
- above the high water level and secured to and supported on said deck along the outer edges thereof from the shore line at one side of the pier around the entire structure to the shore line at the opposite side, a plurality of inflammable piles for supporting the deck above the low water level, and a curtain composed of pre-cast reinforced concrete sections extending from the concrete wall down below the low water level, said sections having their upper ends embedded in the wall to thereby anchor the curtain in place. 40
7. A pier comprising a deck of inflammable material, a concrete wall, extending above the high water level and secured to and supported on said deck along the outer edges thereof from the shore line at one side of the pier around the entire structure to the shore line at the opposite side, a plurality of inflammable piles for supporting the deck above the low water level, and a curtain composed of pre-cast reinforced concrete sections 45 extending from the concrete wall down below the low water level and having their upper ends embedded in the wall to thereby anchor the curtain in place. 50
